DESIGN FOR SCROLL TO BE APPLIED TO ENVELOPES.

The Schedule referred to in these Letters Patent and making part of the same.

TO ALL WHOM IT MAY CONCERN:

Be it known that I, MARO S. CHAPMAN, of the city of Hartford, and State of Connecticut, have originated and designed a new and ornamental Scroll to be Applied to Envelopes, of which the following is a full, clear, and exact description, reference being had to the accompanying specimens or drawings, making part of this specification.

My design consists of a scroll, with three bars, A, B, and C, with the figure of a dove or bird at its upper end, and with the bird in advance of the main portion of the scroll, represented as in the act of flying, and holding the end of the scroll in its beak, as shown.

What I claim as my invention, and desire to secure by Letters Patent, is—

The design for an ornamental scroll, to be applied to envelopes, substantially as shown and described.
